RIBBON MECHANISM FOR TYPE WRITING MACHINES.

(No Model.)

(Application filed July 22, 1899.)

4 Sheets—Sheet 1.

WITNESSES:

Gustave Dietrich
Charles Smith

<img alt="Diagram of a 7x7 grid with numbered circles and a central cross. The grid has 49 numbered circles (1-49) and 4 empty circles. A central cross is formed by circles 25, 26, 27, 28, and 29. Other numbered circles include 39, 41, 43, 45, 47, 49, 51, 53, 55, 57, 59, 61, 63, 65, 67, 69, 71, 73, 75, 77, 79, 81, 83, 85, 87, 89, 91, 93, 95, 97, 99, 101, 103, 105, 107, 109, 111, 113, 115, 117, 119, 121, 123, 125, 127, 129, 131, 133, 135, 137, 139, 141, 143, 145, 147, 149, 151, 153, 155, 157, 159, 161, 163, 165, 167, 169, 171, 173, 175, 177, 179, 181, 183, 185, 187, 189, 191, 193, 195, 197, 199, 201, 203, 205, 207, 209, 211, 213, 215, 217, 219, 221, 223, 225, 227, 229, 231, 233, 235, 237, 239, 241, 243, 245, 247, 249, 251, 253, 255, 257, 259, 261, 263, 265, 267, 269, 271, 273, 275, 277, 279, 281, 283, 285, 287, 289, 291, 293, 295, 297, 299, 301, 303, 305, 307, 309, 311, 313, 315, 317, 319, 321, 323, 325, 327, 329, 331, 333, 335, 337, 339, 341, 343, 345, 347, 349, 351, 353, 355, 357, 359, 361, 363, 365, 367, 369, 371, 373, 375, 377, 379, 381, 383, 385, 387, 389, 391, 393, 395, 397, 399, 401, 403, 405, 407, 409, 411, 413, 415, 417, 419, 421, 423, 425, 427, 429, 431, 433, 435, 437, 439, 441, 443, 445, 447, 449, 451, 453, 455, 457, 459, 461, 463, 465, 467, 469, 471, 473, 475, 477, 479, 481, 483, 485, 487, 489, 491, 493, 495, 497, 499, 501, 503, 505, 507, 509, 511, 513, 515, 517, 519, 521, 523, 525, 527, 529, 531, 533, 535, 537, 539, 541, 543, 545, 547, 549, 551, 553, 555, 557, 559, 561, 563, 565, 567, 569, 571, 573, 575, 577, 579, 581, 583, 585, 587, 589, 591, 593, 595, 597, 599, 601, 603, 605, 607, 609, 611, 613, 615, 617, 619, 621, 623, 625, 627, 629, 631, 633, 635, 637, 639, 641, 643, 645, 647, 649, 651, 653, 655, 657, 659, 661, 663, 665, 667, 669, 671, 673, 675, 677, 679, 681, 683, 685, 687, 689, 691, 693, 695, 697, 699, 701, 703, 705, 707, 709, 711, 713, 715, 717, 719, 721, 723, 725, 727, 729, 731, 733, 735, 737, 739, 741, 743, 745, 747, 749, 751, 753, 755, 757, 759, 761, 763, 765, 767, 769, 771, 773, 775, 777, 779, 781, 783, 785, 787, 789, 791, 793, 795, 797, 799, 801, 803, 805, 807, 809, 811, 813, 815, 817, 819, 821, 823, 825, 827, 829, 831, 833, 835, 837, 839, 841, 843, 845, 847, 849, 851, 853, 855, 857, 859, 861, 863, 865, 867, 869, 871, 873, 875, 877, 879, 881, 883, 885, 887, 889, 891, 893, 895, 897, 899, 901, 903, 905, 907, 909, 911, 913, 915, 917, 919, 921, 923, 925, 927, 929, 931, 933, 935, 937, 939, 941, 943, 945, 947, 949, 951, 953, 955, 957, 959, 961, 963, 965, 967, 969, 971, 973, 975, 977, 979, 981, 983, 985, 987, 989, 991, 993, 995, 997, 999, 1001, 1003, 1005, 1007, 1009, 1011, 1013, 1015, 1017, 1019, 1021, 1023, 1025, 1027, 1029, 1031, 1033, 1035, 1037, 1039, 1041, 1043, 1045, 1047, 1049, 1051, 1053, 1055, 1057, 1059, 1061, 1063, 1065, 1067, 1069, 1071, 1073, 1075, 1077, 1079, 1081, 1083, 1085, 1087, 1089, 1091, 1093, 1095, 1097, 1099, 1101, 1103, 1105, 1107, 1109, 1111, 1113, 1115, 1117, 1119, 1121, 1123, 1125, 1127, 1129, 1131, 1133, 1135, 1137, 1139, 1141, 1143, 1145, 1147, 1149, 1151, 1153, 1155, 1157, 1159, 1161, 1163, 1165, 1167, 1169, 1171, 1173, 1175, 1177, 1179, 1181, 1183, 1185, 1187, 1189, 1191, 1193, 1195, 1197, 1199, 1201, 1203, 1205, 1207, 1209, 1211, 1213, 1215, 1217, 1219, 1221, 1223, 1225, 1227, 1229, 1231, 1233, 1235, 1237, 1239, 1241, 1243, 1245, 1247, 1249, 1251, 1253, 1255, 1257, 1259, 1261, 1263, 1265, 1267, 1269, 1271, 1273, 1275, 1277, 1279, 1281, 1283, 1285, 1287, 1289, 1291, 1293, 1295, 1297, 1299, 1301, 1303, 1305, 1307, 1309, 1311, 1313, 1315, 1317, 1319, 1321, 1323, 1325, 1327, 1329, 1331, 1333, 1335, 1337, 1339, 1341, 1343, 1345, 1347, 1349, 1351, 1353, 1355, 1357, 1359, 1361, 1363, 1365, 1367, 1369, 1371, 1373, 1375, 1377, 1379, 1381, 1383, 1385, 1387, 1389, 1391, 1393, 1395, 1397, 1399, 1401, 1403, 1405, 1407, 1409, 1411, 1413, 1415, 1417, 1419, 1421, 1423, 1425, 1427, 1429, 1431, 1433, 1435, 1437, 1439, 1441, 1443, 1445, 1447, 1449, 1451, 1453, 1455, 1457, 1459, 1461, 1463, 1465, 1467, 1469, 1471, 1473, 1475, 1477, 1479, 1481, 1483, 1485, 1487, 1489, 1491, 1493, 1495, 1497, 1499, 1501, 1503, 1505, 1507, 1509, 1511, 1513, 1515, 1517, 1519, 1521, 1523, 1525, 1527, 1529, 1531, 1533, 1535, 1537, 1539, 1541, 1543, 1545, 1547, 1549, 1551, 1553, 1555, 1557, 1559, 1561, 1563, 1565, 1567, 1569, 1571, 1573, 1575, 1577, 1579, 1581, 1583, 1585, 1587, 1589, 1591, 1593, 1595, 1597, 1599, 1601, 1603, 1605, 1607, 1609, 1611, 1613, 1615, 1617, 1619, 1621, 1623, 1625, 1627, 1629, 1631, 1633, 1635, 1637, 1639, 1641, 1643, 1645, 1647, 1649, 1651, 1653, 1655, 1657, 1659, 1661, 1663, 1665, 1667, 1669, 1671, 1673, 1675, 1677, 1679, 1681, 1683, 1685, 1687, 1689, 1691, 1693, 1695, 1697, 1699, 1701, 1703, 1705, 1707, 1709, 1711, 1713, 1715, 1717, 1719, 1721, 1723, 1725, 1727, 1729, 1731, 1733, 1735, 1737, 1739, 1741, 1743, 1745, 1747, 1749, 1751, 1753, 1755, 1757, 1759, 1761, 1763, 1765, 1767, 1769, 1771, 1773, 1775, 1777, 1779, 1781, 1783, 1785, 1787, 1789, 1791, 1793, 1795, 1797, 1799, 1801, 1803, 1805, 1807, 1809, 1811, 1813, 1815, 1817, 1819, 1821, 1823, 1825, 1827, 1829, 1831, 1833, 1835, 1837, 1839, 1841, 1843, 1845, 1847, 1849, 1851, 1853, 1855, 1857, 1859, 1861, 1863, 1865, 1867, 1869, 1871, 1873, 1875, 1877, 1879, 1881, 1883, 1885, 1887, 1889, 1891, 1893, 1895, 1897, 1899, 1901, 1903, 1905, 1907, 1909, 1911, 1913, 1915, 1917, 1919, 1921, 1923, 1925, 1927, 1929, 1931, 1933, 1935, 1937, 1939, 1941, 1943, 1945, 1947, 1949, 1951, 1953, 1955, 1957, 1959, 1961, 1963, 1965, 1967, 1969, 1971, 1973, 1975, 1977, 1979, 1981, 1983, 1985, 1987, 1989, 1991, 1993, 1995, 1997, 1999, 2001, 2003, 2005, 2007, 2009, 2011, 2013, 2015, 2017, 2019, 2021, 2023, 2025, 2027, 2029, 2031, 2033, 2035, 2037, 2039, 2041, 2043, 2045, 2047, 2049, 2051, 2053, 2055, 2057, 2059, 2061, 2063, 2065, 2067, 2069, 2071, 2073, 2075, 2077, 2079, 2081, 2083, 2085, 2087, 2089, 2091, 2093, 2095, 2097, 2099, 2101, 2103, 2105, 2107, 2109, 2111, 2113, 2115, 2117, 2119, 2121, 2123, 2125, 2127, 2129, 2131, 2133, 2135, 2137, 2139, 2141, 2143, 2145, 2147, 2149, 2151, 2153, 2155, 2157, 2159, 2161, 2163, 2165, 2167, 2169, 2171, 2173, 2175, 2177, 2179, 2181, 2183, 2185, 2187, 2189, 2191, 2193, 2195, 2197, 2199, 2201, 2203, 2205, 2207, 2209, 2211, 2213, 2215, 2217, 2219, 2221, 2223, 2225, 2227, 2229, 2231, 2233, 2235, 2237, 2239, 2241, 2243, 2245, 2247, 2249, 2251, 2253, 2255, 2257, 2259, 2261, 2263, 2265, 2267, 2269, 2271, 2273, 2275, 2277, 2279, 2281, 2283, 2285, 2287, 2289, 2291, 2293, 2295, 2297, 2299, 2301, 2303, 2305, 2307, 2309, 2311, 2313, 2315, 2317, 2319, 2321, 2323, 2325, 2327, 2329, 2331, 2333, 2335, 2337, 2339, 2341, 2343, 2345, 2347, 2349, 2351, 2353, 2355, 2357, 2359, 2361, 2363, 2365, 2367, 2369, 2371, 2373, 2375, 2377, 2379, 2381, 2383, 2385, 2387, 2389, 2391, 2393, 2395, 2397, 2399, 2401, 2403, 2405, 2407, 2409, 2411, 2413, 2415, 2417, 2419, 2421, 2423, 2425, 2427, 2429, 2431, 2433, 2435, 2437, 2439, 2441, 2443, 2445, 2447, 2449, 2451, 2453, 2455, 2457, 2459, 2461, 2463, 2465, 2467, 2469, 2471, 2473, 2475, 2477, 2479, 2481, 2483, 2485, 2487, 2489, 2491, 2493, 2495, 2497, 2499, 2501, 2503, 2505, 2507, 2509, 2511, 2513, 2515, 2517, 2519, 2521, 2523, 2525, 2527, 2529, 2531, 2533, 2535, 2537, 2539, 2541, 2543, 2545, 2547, 2549, 2551, 2553, 2555, 2557, 2559, 2561, 2563, 2565, 2567, 2569, 2571, 2573, 2575, 2577, 2579, 2581, 2583, 2585, 2587, 2589, 2591, 2593, 2595, 2597, 2599, 2601, 2603, 2605, 2607, 2609, 2611, 2613, 2615, 2617, 2619, 2621, 2623, 2625, 2627, 2629, 2631, 2633, 2635, 2637, 2639, 2641, 2643, 2645, 2647, 2649, 2651, 2653, 2655, 2657, 2659, 2661, 2663, 2665, 2667, 2669, 2671, 2673, 2675, 2677, 2679, 2681, 2683, 2685, 2687, 2689, 2691, 2693, 2695, 2697, 2699, 2701, 2703, 2705, 2707, 2709, 2711, 2713, 2715, 2717, 2719, 2721, 2723, 2725, 2727, 2729, 2731, 2733, 2735, 2737, 2739, 2741, 2743, 2745, 2747, 2749, 2751, 2753, 2755, 2757, 2759, 2761, 2763, 2765, 2767, 2769, 2771, 2773, 2775, 2777, 2779, 2781, 2783, 2785, 2787, 2789, 2791, 2793, 2795, 2797, 2799, 2801, 2803, 2805, 2807, 2809, 2811, 2813, 2815, 2817, 2819, 2821, 2823, 2825, 2827, 2829, 2831, 2833, 2835, 2837, 2839, 2841, 2843, 2845, 2847, 2849, 2851, 2853, 2855, 2857, 2859, 2861, 2863, 2865, 2867, 2869, 2871, 2873, 2875, 2877, 2879, 2881, 2883, 2885, 2887, 2889, 2891, 2893, 2895, 2897, 2899, 2901, 2903, 2905, 2907, 2909, 2911, 2913, 2915, 2917, 2919, 2921, 2923, 2925, 2927, 2929, 2931, 2933, 2935, 2937, 2939, 2941, 2943, 2945, 2947, 2949, 2951, 2953, 2955, 2957, 2959, 2961, 2963, 2965, 2967, 2969, 2971, 2973, 2975, 2977, 2979, 2981, 2983, 2985, 2987, 2989, 2991, 2993, 2995, 2997, 2999, 3001, 3003, 3005, 3007, 3009, 3011, 3013, 3015, 3017, 3019, 3021, 3023, 3025, 3027, 3029, 3031, 3033, 3035, 3037, 3039, 3041, 3043, 3045, 3047, 3049, 3051, 3053, 3055, 3057, 3059, 3061, 3063, 3065, 3067, 3069, 3071, 3073, 3075, 3077, 3079, 3081, 3083, 3085, 3087, 3089, 3091, 3093, 3095, 3097, 3099, 3101, 3103, 3105, 3107, 3109, 3111, 3113, 3115, 3117, 3119, 3121, 3123, 3125, 3127, 3129, 3131, 3133, 3135, 3137, 3139, 3141, 3143, 3145, 3147, 3149, 3151, 3153, 3155, 3157, 3159, 3161, 3163, 3165, 3167, 3169, 3171, 3173, 3175, 3177, 3179, 3181, 3183, 3185, 3187, 3189, 3191, 3193, 3195, 3197, 3199, 3201, 3203, 3205, 3207, 3209, 3211, 3213, 3215, 3217, 3219, 3221, 3223, 3225, 3227, 3229, 3231, 3233, 3235, 3237, 3239, 3241, 3243, 3245, 3247, 3249, 3251, 3253, 3255, 3257, 3259, 3261, 3263, 3265, 3267, 3269, 3271, 3273, 3275, 3277, 3279, 3281, 3283, 3285, 3287, 3289, 3291, 3293, 3295, 3297, 3299, 3301, 3303, 3305, 3307, 3309, 3311, 3313, 3315, 3317, 3319, 3321, 3323, 3325, 3327, 3329, 3331, 3333, 3335, 3337, 3339, 3341, 3343, 3345, 3347, 3349, 3351, 3353, 3355, 3357, 3359, 3361, 3363, 3365, 3367, 3369, 3371, 3373, 3375, 3377, 3379, 3381, 3383, 3385, 3387, 3389, 3391, 3393, 3395, 3397, 3399, 3401, 3403, 3405, 3407, 3409, 3411, 3413, 3415, 3417, 3419, 3421, 3423, 3425, 3427, 3429, 3431, 3433, 3435, 3437, 3439, 3441, 3443, 3445, 3447, 3449, 3451, 3453, 3455, 3457, 3459, 3461, 3463, 3465, 3467, 3469, 3471, 3473, 3475, 3477, 3479, 3481, 3483, 3485, 3487, 3489, 3491, 3493, 3495, 3497, 3499, 3501, 3503, 3505, 3507, 3509, 3511, 3513, 3515, 3517, 3519, 3521, 3523, 3525, 3527, 3529, 3531, 3533, 3535, 3537, 3539, 3541, 3543, 3545, 3547, 3549, 3551, 3553, 3555, 3557, 3559, 3561, 3563, 3565, 3567, 3569, 3571, 3573, 3575, 3577, 3579, 3581, 3583, 3585, 3587, 3589, 3591, 3593, 3595, 3597, 3599, 3601, 3603, 3605, 3607, 3609, 3611, 3613, 3615, 3617, 3619, 3621, 3623, 3625, 3627, 3629, 3631, 3633, 3635, 3637, 3639, 3641, 3643, 3645, 3647, 3649, 3651, 3653, 3655, 3657, 3659, 3661, 3663, 3665, 3667, 3669, 3671, 3673, 3675, 3677, 3679, 3681, 3683, 3685, 3687, 3689, 3691, 3693, 3695, 3697, 3699, 3701, 3703, 3705, 3707, 3709, 3711, 3713, 3715, 3717, 3719, 3721, 3723, 3725, 3727, 3729, 3731, 3733, 3735, 3737, 3739, 3741, 3743, 3745, 3747, 3749, 3751, 3753, 3755, 3757, 3759, 3761, 3763, 3765, 3767, 3769, 3771, 3773, 3775, 3777, 3779, 3781, 3783, 3785, 3787, 3789, 3791, 3793, 3795, 3797, 3799, 3801, 3803, 3805, 3807, 3809, 3811, 3813, 3815, 3817, 3819, 3821, 3823, 3825, 3827, 3829, 3831, 3833, 3835, 3837, 3839, 3841, 3843, 3845, 3847, 3849, 3851, 3853, 3855, 3857, 3859, 3861, 3863, 3865, 3867, 3869, 3871, 3873, 3875, 3877, 3879, 3881, 3883, 3885, 3887, 3889, 3891, 3893, 3895, 3897, 3899, 3901, 3903, 3905, 3907, 3909, 3911, 3913, 3915, 3917, 3919, 3921, 3923, 3925, 3927, 3929, 3931, 3933, 3935, 3937, 3939, 3941, 3943, 3945, 3947, 3949, 3951, 3953, 3955, 3957, 3959, 3961, 3963, 3965, 3967, 3969, 3971, 3973, 3975, 3977, 3979, 3981, 3983, 3985, 3987, 3989, 3991, 3993, 3995, 3997, 3999, 4001, 4003, 4005, 4007, 4009, 4011, 4013, 4015, 4017, 4019, 4021, 4023, 4025, 4027, 4029, 4031, 4033, 4035, 4037, 4039, 4041, 4043, 4045, 4047, 4049, 4051, 4053, 4055, 4057, 4059, 4061, 4063, 4065, 4067, 4069, 4071, 4073, 4075, 4077, 4079, 4081, 4083, 4085, 4087, 4089, 4091, 4093, 4095, 4097, 4099, 4101, 4103, 4105, 4107, 4109, 4111, 4113, 4115, 4117, 4119, 4121, 4123, 4125, 4127, 4129, 4131, 4133, 4135, 4137, 4139, 4141, 4143, 4145, 4147, 4149, 4151, 4153, 4155, 4157, 4159, 4161, 4163, 4165, 4167, 4169, 4171, 4173, 4175, 4177, 4179, 4181, 4183, 4185, 4187, 4189, 4191, 4193, 4195, 4197, 4199, 4201, 4203, 4205, 4207, 4209, 4211, 4213, 4215, 4217, 4219, 4221, 4223, 4225, 4227, 4229, 4231, 4233, 4235, 4237, 4239, 4241, 4243, 4245, 4247, 4249, 4251, 4253, 4255, 4257, 4259, 4261, 4263, 4265, 4267, 4269, 4271, 4273, 4275, 4277, 4279, 4281, 4283, 4285, 4287, 4289, 4291, 4293, 4295, 4297, 4299, 4301, 4303,

UNITED STATES PATENT OFFICE.

HERMAN L. WAGNER, OF BROOKLYN, AND FRANK L. WAGNER, OF NEW YORK, N. Y., ASSIGNORS TO THE WAGNER TYPEWRITER COMPANY, OF NEW YORK, N. Y.

RIBBON MECHANISM FOR TYPE-WRITING MACHINES.

SPECIFICATION forming part of Letters Patent No. 670,600, dated March 26, 1901.

Original application filed July 9, 1898, Serial No. 685,512. Divided and this application filed July 22, 1899. Serial No. 724,756. (No model.)

To all whom it may concern:

Be it known that we, HERMAN L. WAGNER, residing in the borough of Brooklyn, Kings county, and FRANK L. WAGNER, residing in the city and county of New York, State of New York, citizens of the United States, have invented certain new and useful Improvements in Ribbon Mechanism for Type-Writing Machines, of which the following is a full, clear, and exact description.

Our present invention relates to ribbon mechanism for type-writing machines; and the subject-matter embodied herein is a division of that included in our application, Serial No. 685,512, filed on the 9th day of July, 1898, for type-writing machines.

The object of the present invention is to provide a simple and efficient ribbon mechanism more particularly adapted for "front-strike" or "visible writing" machines, though obviously the invention may be applied to any type-writing machine wherein its application may be found feasible.

This invention consists in the novel arrangement and combination of parts to be hereinafter described and claimed.

In the accompanying drawings, wherein like reference characters designate corresponding parts in the various views, Figure 1 is an end view of one form of machine embodying our invention with parts removed for the purpose of clearer illustration. Fig. 2 is a front view of the same. Fig. 3 is a plan view of the machine with parts omitted for the purpose of clearer illustration. Fig. 4 is an enlarged detail front view of one of the ribbon-spool-operating clutches, the spool being shown removed from its spindle. Fig. 5 is a like view of the same with parts in section, the spool being shown in place. Fig. 6 is an enlarged detail fragmentary sectional view of a portion of the machine. Fig. 7 is an enlarged fragmentary detail side view of one of the clutches for operating the spool. Fig. 8 is a like view of the same looking from an opposite direction. Fig. 9 is a fragmentary enlarged detail sectional view of a portion of the ribbon-spool feed mechanism.

Reference being had to the accompanying

drawings, forming part hereof and wherein 50 one form of type-writing machine is illustrated embodying our invention, 1 designates the main frame of the machine, in which most of the working parts are carried. Secured to the frame 1 is a segmental plate 2, 55 in which the type-bar carriers 3 are pivoted, so that the printing characters on each type-bar are adapted to be brought to the printing-point, as will hereinafter more fully appear. Each of the type-bar carriers 3 carries 60 a swiveled type-bar 4, provided with a type-block 5, having a plurality of faces carrying printing characters. Two of the faces of the type-block are provided with types or characters in the present instance, one face carrying 65 an upper-case character and another face carrying a lower-case character. Suitable coöperating mechanism is provided to give when desired a partial rotation to each of the type-bars in the movement thereof to 70 the printing-point on the platen 6, so as to bring an upper-case character into operation; but inasmuch as this mechanism does not constitute a feature of the present case, but is included in the application hereinbefore referred to, no further description thereof is 75 deemed necessary.

Operatively connected to each of the type-bar carriers 3—as, for instance, by means of a pin-and-slot connection 7—is a reciprocating slide 8, which is provided at its rear end with a hook 9. (See Fig. 6.) This hook 9 is open toward the front of the machine and is adapted to engage a segmental universal bar 10 when the slide is moved forward toward 80 the front of the machine, but is free to move in an opposite direction independently of said universal bar. The universal bar 10 is rigidly connected to suitably-guided slides 11 and 12. The slide 11 performs no other function than 85 a slide for supporting and guiding the universal bar; but the slide 12 is provided with a cam finger or abutment 13, which is adapted to contact and coöperate with a crank-arm 14, connected to a rock-shaft 15, suitably mounted in a bracket 16, Fig. 2, carried by a fixed portion of the machine. The rock-shaft 15 likewise carries a ribbon-guide 17, com-

prising two fingers, one of which extends to each side of the ribbon 18.

From an examination of Fig. 1 of the drawings it will be observed that one edge of the 5 ribbon is adjacent to and substantially in line with the rock-shaft 15, which constitutes the pivot on which the ribbon turns. By this construction the ribbon is normally maintained in a plane that intersects the vertical 10 diameter of the platen and is automatically turned on its edge to interpose the body thereof in the path of the type when a type-bar is moved to the printing-point, as represented in Fig. 6 of the drawings. By these 15 means a very short movement of the ribbon around one edge thereof is sufficient to not only expose the last word or letter written, but to fully expose the entire last line printed to the operator. When the type-bar moves 20 back to the initial position, the ribbon-guide will be automatically turned to the position represented in Fig. 1 to expose the character just impressed upon the paper by the type. This movement is due to the fact that the 25 finger 13 is moved back with the universal bar 10 and is no longer effective to maintain the ribbon-guide in the position represented in Fig. 6 when the ribbon-guide is moved back by suitable means, or the tension of the 30 ribbon exerted thereon may be sufficient for this purpose.

The universal bar 10 is pivoted, as indicated at 18^x, Figs. 1 and 2, to upright arms 19, fixed upon a rock-shaft 20, pivoted to the 35 framing of the machine. This rock-shaft 20 likewise has an arm 21 secured thereto, which arm is adapted to coöperate with an arm 22, Fig. 1, of a cruciform lever 23, pivoted to a bracket, as indicated at 23^x in Figs. 2 and 3. 40 The other three arms of this cruciform lever 23 are indicated at 24, 25, and 26. The arm 26 has a retractile spring 27 connected thereto in order to restore the cruciform lever 23 and the parts connected thereto to the normal position. 45 The forward arm 25 of the lever 23 is provided with a pin 28, Figs. 1 and 3, which overlies the free end 29 of a spacing-lever 30, carrying a spacing key or bar 31 at its outer end. This spacing-lever is pivoted at 32, and the outer 50 end thereof is normally maintained in the elevated position by a spring 33. The upwardly-projecting arm 24 of the lever 23 is pivoted to a link 34, as indicated at 35, and the opposite end of this link is connected to a rocking 55 frame 36, which carries the feed-dogs 37 and 38 and is pivoted at 39. The feed-dogs co-operate with a feed-rack 40, suitably carried by the reciprocating platen-carriage 41 of the machine. From this construction it will be 60 seen that when the spacing-key 31 is depressed motion will be transmitted to the cruciform lever 23 to rock the same backward to impart movement to the link 34, which moves the frame 36 and the feed-dogs 37 and 38, connected thereto, thus feeding the carriage the distance between two letters when the parts are restored to their normal position.

The key-levers 42 are each provided with a finger-key 43 and an upwardly-extending arm 44, which is connected to a corresponding slide 8—as, for instance, by means of a pin-and-slot connection 45. Each of the key-levers 42 is pivoted, as at 46, to a bracket 47, projecting from the bed-plate of the machine, so that when a key 43 is depressed the arm 44 thereof is moved forward and moves with it the corresponding slide 8, and its type-bar 3 is moved to the printing-point. This movement of the slide 8 causes the universal bar 10 to be moved forward, thus imparting motion to the slide 12, which causes the ribbon to be turned into the path of the type on the type-bar before said type has reached the printing-point. This same movement of the universal bar transmits a rocking motion to 85 the rock-shaft 20 through the arms 19, and the rocking of the shaft 20 causes the cruciform lever 23 to be rocked on its pivot by the arm 21 depressing the arm 22 on said lever. In this manner a depression of a key-lever 90 will simultaneously rock the ribbon into and out of the path of a printing character and will operate the feed mechanism of the carriage. This movement likewise causes the automatic feed of the ribbon in the direction 95 of its length, as will hereinafter appear.

To a fixed bracket 48 at each end of the machine are secured most of the parts of the ribbon-feed mechanism, the ribbon passing from spool 49 to spool 49 over suitable guide-rollers 50, one at each end or side of the machine. Each of the spools 49 is adapted to have a sleeve 51 projected through a central aperture therein. Each of the sleeves 51 rotates upon a fixed pintle 52, Fig. 5, projecting 100 from a bracket 48, and they are each provided with a laterally-projecting arm 53, secured thereto. Each of these arms has pivoted, as at 54, a spring-pressed catch 55, which is adapted to pass through an aperture 56 in its coöperating spool, which aperture is located to one side of the center of rotation of said spool. The shoulder 57 of the catch bears against the body portion of the spool and locks the same against removal from the sleeve 52 until 115 the free end 58 of said catch is pressed by hand to one side to permit the spool to be withdrawn. By these means it will be seen that the catch of each spool not only locks its spool to the sleeve 52 for rotation therewith, but 120 each catch at the same time affords means for rotating its spool by hand by reason of the position of each catch in its engagement with its respective spool. Each of the sleeves 52 likewise carries a friction-disk 59, which 125 rotates therewith, and coöperating with this friction-wheel is a clutch-roller 60, which is loosely carried by trunnions 60^x, projecting in the elongated bearings 61 of the swinging roller-carrying yoke 62, which is pivoted to 130 a feeding-yoke 63, as indicated at 64. Each of the feeding-yokes 63 is pivoted upon a sleeve 52, as indicated at 65, and moves independently thereof. Projecting from each

of the yokes 63 and at each side thereof is a cam-arm 66, whose cam-face is eccentric to the periphery of the coöperating friction-disk 59, and these arms are adapted to support a clutch-roller 60, so that as the feeding-yoke 63 is moved in the direction of the arrow α in Fig. 7 the roller will be jammed between the cam-faces of the arms 66 and the periphery of the coöperating friction-disk, and thus 10 lock the parts to move together. The movement of yoke 63 in an opposite direction from that indicated by the arrow α will not effect a movement of the friction-disk, because the clutch-roller will move to the lower 15 portion of the cams on the arms and be maintained out of contact with the periphery of the disk. By having the trunnions of each of the clutch-rollers 60 seated in the yoke 62 in the manner described we are enabled to 20 throw said clutch-roller out of action at will, and the roller may be maintained out of action by the latch 67, pivoted at 68 to the yoke 63, as will hereinafter more fully appear. A retractile spring 69 is connected at one end 25 to the latch 67 and at the other end to the yoke 62, so as to normally maintain the parts in the positions represented in Fig. 7, where- 30 in the clutch-roller is maintained in operation. By turning the finger 70 in the direc- 35 tion of the arrow α , Fig. 7, the finger will first be brought into contact with the face 71 of the yoke 62 and force it against the ten- 40 sion of the spring 69, which permits the abut- 45 ment 72 on the latch 67 to drop under the nose 73 on the yoke 62, and thus maintain the clutch-roller 60 out of action. A further 50 rotation of the finger 70 will cause it to abut against the arm 74 of the latch 67 and move it upon its pivot. This movement of the 55 latch releases the yoke 62 and again permits the clutch-roller 60 to be brought into en- 60 gagement with its coöperating friction-disk, as represented in Fig. 7 of the drawings. A friction-brake 75 bears upon the periphery of 65 each disk 59 and prevents a retrograde move- 70 ment being imparted thereto. It should be understood that the ribbon mechanism on each side of the machine is the same except that the fingers 70, which are carried upon a 75 revoluble shaft 76, are oppositely disposed, so that when one of said fingers maintains its clutch-roller in the operative position the other finger will have moved its clutch-roller to the inoperative position. This shaft 76 80 extends from end to end of the machine and is provided at one end with a finger-piece 77, Figs. 4 and 5, by which it can be turned to throw the proper spool into operation and to simultaneously throw the other spool out of 85 operation. In order that the shaft may be turned in only one direction, we provide a stop-piece 78, Fig. 8, which is carried upon the shaft 76 and is provided with abutments 79, that coöperate with a leaf-spring 80 to 90 prevent the shaft from being rotated in the direction of the arrow in Fig. 8, but permit

a free rotation of the shaft in an opposite di- 95 rection.

Motion is communicated to the yokes 63 to feed the ribbon-spools by arms 81, Fig. 8, ad- 70 justably secured upon the rock-shaft 20, one of said arms being provided for each ribbon- 75 spool. These arms each carry an adjustable sleeve 82, which has a laterally-projecting pin 83, that extends into a slotted arm 84 of a yoke 63. By this arrangement a back-and- 80 forth movement is imparted to both the yokes 63 at each feed of the carriage, and the yoke which has its clutch-roller in engagement with its disk 59 will impart a movement to its 85 ribbon-spool, while the opposite ribbon-spool will remain inactive. The adjustment of the sleeve 82 permits a longer or shorter throw to be given to each of the yokes 63 and a consequent longer or shorter feed movement to be 90 given the ribbon.

It will be observed that by this mechanism we are able to obtain various degrees of movement of the ribbon, and that unlike ratchet-feed movements the mechanism can be ad- 95 justed to use any and every portion of the ribbon in the direction of its length.

From the foregoing description it is thought a clear understanding of the operation of our device will be had and that no detailed de- 95 scription of the operation need be given.

Having described our invention, what we claim, and desire to secure by Letters Patent, is—

1. In a front-strike type-writing machine, 100 the combination of a platen, printing mechanism, a ribbon normally maintained in a horizontal plane that intersects the vertical di- 105 ameters of the platen to expose the writing thereon to the operator, a pivoted ribbon- 110 guide, the pivotal axis of which is substan- 115 tially in line with the edge of the ribbon ad- jacent to the platen, a universal bar and a slide fixed to said universal bar for automatically turning said ribbon-guide upwardly on its pivot so as to interpose the ribbon in the path of the printing mechanism during the printing stroke thereof, whereby the ribbon is normally maintained in a position to ex- 120 pose the line being printed to the view of the operator.

2. In a type-writing machine, the combina- 120 tion of a series of type-bars, finger-keys for operating said type-bars, ribbon-spools, au- 125 tomatically-operated reciprocating frictional mechanism coöperating with both of the ribbon-spools and controlled by said finger-keys for imparting an intermittent rotary motion to either of said spools and a platen-carriage operable by hand independently of said frictional mechanism.

3. In a type-writing machine, the combina- 130 tion of ribbon-spools, spacing mechanism, automatically-operated frictional mechanism every movement of which is controlled by the spacing mechanism for imparting an inter- 135 mittent rotary motion to either of said spools

and means for controlling said frictional mechanism so that when it is effective to operate one of said spools, it will be ineffective to operate the other whereby the ribbon may be alternately fed in opposite directions.

4. In a type-writing machine, the combination of a platen-carriage, spacing mechanism for said carriage, rotary disks, an automatically-operated reciprocating frictional clutch for each of said disks, said clutches being operable to transmit an intermittent rotary motion to said disks in one direction and free to move independently thereof in an opposite direction and ribbon-spools operatively connected to said disks, whereby the ribbon may be fed alternately from one spool to another.

5. In a type-writing machine, the combination of a platen-carriage, spacing mechanism for said carriage, rotary disks, reciprocating frictional clutches which are operated by the spacing mechanism and transmit an intermittent rotary motion to said disks, ribbon-spools operatively connected to said disks and hand-operated mechanism for operating said ribbon-spools by hand independently of the automatic operation thereof.

6. In a type-writing machine, the combination of a platen-carriage, spacing mechanism for said carriage, rotary disks, intermittently-operated reciprocating frictional clutches which are operated by the spacing mechanism and which transmit an intermittent rotary motion to said disks, ribbon-spools operatively connected to said disks, hand-operated mechanism for operating the said ribbon-spools by hand independently of the automatic operation thereof and means for throwing either of said friction-clutches out of operation at will.

7. In a type-writing machine, the combination of a platen-carriage, spacing mechanism for said carriage, rotary disks, automatically-operated reciprocating friction-clutches, each adapted to automatically engage a disk when

45 moving in one direction and to automatically be disengaged therefrom when moving in an opposite direction, whereby an intermittent rotary motion is transmitted to said disks, means for changing the extent of throw of said clutches, ribbon-spools operatively connected to said disks and means for retaining said clutches out of engagement with said disks.

8. In a ribbon-feeding mechanism for type-writing machines, the combination of a rotary friction-disk, a ribbon-spool operatively connected thereto and an automatically-operated clutch for transmitting motion to said friction-disk, said clutch comprising a movable cam and a clutch-roller supported upon said cam and adapted to be conveyed thereby into and out of contact with the periphery of said disk.

9. In a ribbon-feeding mechanism for type-writing machines, the combination of a rotary friction-disk, a ribbon-spool operatively connected thereto and an automatically-operated

clutch for transmitting motion to said friction-disk, said clutch comprising an intermittently-oscillated feeding-yoke carrying a cam and a clutch-roller supported upon said cam and adapted to be conveyed thereby into and out of contact with the periphery of said disk to lock the disk to move with the yoke when the latter is moved in one direction and to permit the yoke to move independently of the disk when the yoke is moved in an opposite direction.

10. In a ribbon-feeding mechanism for type-writing machines, the combination of a rotary friction-disk, a ribbon-spool operatively connected thereto, an automatically-operated clutch for transmitting motion to said friction-disk, said clutch comprising a movable cam and a clutch-roller supported upon said cam and adapted to be conveyed thereby into and out of contact with the periphery of said disk and means independent of said cam for maintaining the roller at the lower part thereof and out of contact with the periphery of the disk.

11. In a ribbon-feeding mechanism for type-writing machines, the combination of a rotary friction-disk, a ribbon-spool operatively connected thereto, an automatically-operated clutch for transmitting motion to said friction-disk, said clutch comprising an intermittently-oscillated feeding-yoke carrying a cam and a clutch-roller supported upon said cam and adapted to be conveyed thereby into and out of contact with the periphery of said disk to lock the disk to move with the yoke when the latter is moved in one direction and to permit the yoke to move independently of the disk when the yoke is moved in an opposite direction and a clutch-roller yoke independent of said feeding-yoke for maintaining the roller at the lower part of the cam and out of contact with the periphery of the disk, whereby the feeding-yoke can be oscillated without imparting motion to the disk.

12. The combination of a ribbon-spool, a catch adapted to secure the spool in place and projecting beyond the face thereof when the spool is in place so as to constitute a handle therefor and means for rotating the said catch so as to transmit movement to the ribbon-spool.

13. In a type-writing machine, the combination of oppositely-located ribbon-spools, friction-clutches, means for reciprocating said clutches to automatically and intermittently rotate the spools and a hand-operated shaft extending across the machine and provided with fingers which coöperate with the clutch and arranged to alternately throw said friction-clutches into and out of operation and thereby change the feed of the ribbon in a longitudinal direction.

14. In a type-writing machine, the combination of a ribbon-spool, a reciprocating clutch-roller, a friction-disk with which said clutch-roller coöperates, a coöperating relatively-inclined abutting surface for said roller

and means for reciprocating said roller, whereby when said roller is reciprocated in one direction it will be jammed to intermittently rotate the ribbon-spool and when reciprocated in an opposite direction will move out of the jammed or engaging position.

15. In a type-writing machine, the combination of a ribbon-spool, a reciprocating clutch-roller adapted to intermittently rotate said spool when moved bodily in one direction and to move automatically out of the engaging position when moved bodily in an opposite direction, means for reciprocating said roller and means for varying the throw of said clutch-roller.

16. In a type-writing machine, the combination of a ribbon-spool, a friction-clutch adapted to intermittently rotate said ribbon-spool, means for intermittently moving said clutch and means for varying the throw of said clutch.

17. The combination of an oscillating feed-

yoke, a clutch-roller carried by said yoke, a friction-disk with which said roller cooperates, a ribbon-spool operatively connected to said friction-disk and means for varying the throw of said feed-yoke.

18. The combination of an oscillating feed-yoke, a clutch-roller carried by said yoke, a friction-disk with which said roller cooperates and with which the roller locks when the yoke is moved in one direction and which is free therefrom when the yoke is moved in an opposite direction, a ribbon-spool operatively connected to said friction-disk, means for varying the throw of said feed-yoke and means for maintaining the clutch-roller out of operation when desired.
